[57] CLAIM

The ornamental design for an emergency floatation for boats, as shown and described.

DESCRIPTION

FIG. 1 is a front elevation view of an emergency flotation for boats showing my new design;

FIG. 2 is a top plan view thereof;

FIG. 3 is a right end elevational view thereof; and

FIG. 4 is a perspective view thereof, showing the design in normal position for use. The broken lines are for illustrative purposes only and form no part of the claimed design.

FIG 2

FIG 1
